UNITED STATES PATENT OFFICE.

EMIL BOSER AND EARNEST MATZ, OF HOLLYWOOD, CALIFORNIA.

NON-REFILLABLE BOTTLE.

1,133,225.

Specification of Letters Patent. Patented Mar. 23, 1915.

Application filed April 8, 1914. Serial No. 880,466.

To all whom it may concern:

Be it known that we, EMIL BOSER and EARNEST MATZ, citizens of the United States, residing at Hollywood, in the county 5 of Los Angeles and State of California, have invented new and useful Improvements in Non-Refillable Bottles, of which the following is a specification.

The invention relates to bottles and more 10 particularly to bottles of the non-refillable type and has for an object to provide a bottle which can not be conveniently refilled with another or inferior fluid after the original contents have once been with- 15 drawn therefrom.

The invention contemplates among other 20 features the provision of a non-refillable bottle which has the neck thereof so arranged and constructed and coöperating with a ball valve that after the bottle has 25 once been filled it can not be conveniently refilled, upon being emptied thus preventing persons other than the manufacturers or distributers of the original contents of the 30 bottle from refilling the bottle with a spurious or inferior fluid.

In the further disclosure of the invention 35 reference is to be had to the accompanying drawings, constituting a part of this specification in which similar characters of reference denote corresponding parts in all the 40 views, and in which:—

Figure 1 is a fragmentary vertical sectional view of the bottle showing the same 45 in upright and sealed position the bottle being filled with the original fluid, Fig. 2 is a fragmentary vertical sectional view showing the intermediate position of the bottle valve, Fig. 3 is a fragmentary vertical sectional 50 view showing the position of the bottle valve after the bottle has been emptied, and Fig. 4 is a horizontal sectional view taken on the line 4—4 in Fig. 1.

Referring more particularly to the views 55 we provide a bottle body 10 including an integral neck 11, said neck being of a tubular nature and including a bulged portion forming a chamber 12 and a correspondingly restricted portion constituting a passage 13.

The neck 11 at its lower end is restricted to 60 form a valve seat 14 which we will term the lower valve seat and above the bulged portion forming the chamber 12 the neck is again restricted to form a second valve seat 65 15 and which we will term the intermediate valve seat. Near its upper end the neck is

again restricted to form a third valve seat 16 which I will term the upper valve seat, the latter valve seat being formed at the mouth of the passage 13.

The medial portion of the neck 11 and 70 which is restricted to form the intermediate valve seat 15 provides a circular depending flange 17 which forms the intermediate valve seat and this flange is preferably provided 75 with a plurality of openings or passages 18 through which the fluid is adapted to flow. A ball valve 19 is provided and is formed and constructed so that it can be slightly compressed. To this end the ball valve may 80 be formed of rubber or it may consist of a glass core encircled by rubber. It will be understood that we do not limit ourselves to the particular construction of the ball valve except that it shall be slightly compressible. 85 This ball valve is adapted to repose upon the upper valve seat 16 and after the bottle body has been initially filled with the desired fluid it will be seen that the ball valve when arranged upon the upper valve 90 seat will effectively seal the bottle as shown in Fig. 1. Now when it is desired to pour the contents of the bottle therefrom a downward pressure is exerted on the ball valve thus releasing or disengaging the same from the upper valve seat and permitting it to gravitate onto the intermediate valve seat with which it will frictionally contact and will 95 thus be held stationary. It will be apparent that when the ball valve is in this position 100 as shown in Fig. 2, the tilting of the bottle will result in the contents thereof being poured therefrom, said fluid passing through the chamber 12 and the openings or passages 18, into the passage 13 and from which it 105 will be poured out of the neck when the bottle valve rests upon the intermediate valve seat. Now after the original contents of the bottle have been withdrawn therefrom a second downward pressure is exerted 110 on the ball valve thus disengaging the same from the intermediate valve seat and permitting it to drop on to and frictionally contact with the lower valve seat 14. The ball valve when in engagement with the 115 lower valve seat will effectively close the bottle body and it will be readily seen that the bottle body cannot be conveniently filled when in an upright position for the reason that the ball valve will close the lower portion 120 of the neck which communicates with the interior of the bottle body. Assuming

- that the bottle body is inverted for the purpose of refilling the ball valve will prevent the fluid from being forced upwardly through the passage 13 and chamber 12 into the interior of the bottle body, it being rigidly held on the lower valve seat as mentioned. If desirable a rod or some other suitable implement can be used to force the ball valve from one seat to the other and 5
- 10 with this instrument the ball valve can be jammed into engagement with the lower valve seat after the bottle body has been emptied. On account of the smooth circular surface of the ball valve it would hardly 15 be possible to insert another instrument into the neck of the bottle and remove the ball valve from its engagement with the lower valve seat.

From the foregoing description it will 20 be apparent that the bottle consists of but two parts namely the bottle body having an integral neck and the ball valve arranged to operate in the neck. It will be noted that the device set forth can be cheaply manufactured; cannot readily get out of order 25 on account of its simplicity and can be easily operated to accomplish the desired results.

What we claim is:—

- 30 In a non-refillable bottle, a bottle body having a neck provided with a bulged portion, a lower valve seat in the neck and

formed at the juncture of the neck with the bottle body, an intermediate valve seat in the neck, and an upper valve seat in the 35 neck formed adjacent the mouth of the neck, said valve seats being spaced apart, a resilient ball valve normally reposing on the upper valve seat to initially seal the bottle body, said ball valve being movable 40 to engage and repose upon the intermediate valve seat and further movable out of engagement with the intermediate valve seat to engage and repose upon the lower valve seat to seal the bottle body after the same 45 has been emptied to prevent refilling, said intermediate valve seat being formed by an inwardly projecting extension of the upper portion of the neck, lying within the bulged portion of the neck and spaced therefrom, 50 and a series of passages formed in the said inward extension and adapted to be unrestricted by the ball valve when the same is on the intermediate valve seat to permit of pouring the contents of said bottle body 55 therefrom when said ball valve is on said intermediate valve seat.

In testimony whereof we affix our signatures in presence of two witnesses.

MR. EMIL BOSER.
MR. EARNEST MATZ.
